JEWELRY HOLDER OR SIMILAR ARTICLE

Madeleine W. Galland, New York, N.Y.

Application November 17, 1958, Serial No. 53,406

Term of patent 3½ years

(Cl. D86—10)

Fig. 1

Fig. 2

Fig. 3

Fig. 4

Figure 4 is a top plan view on reduced scale as it appears with the clamping element in closed position; and

I claim:

The ornamental design for a jewelry holder or similar article, as shown.
